[57] CLAIM

The ornamental design for a bottle draining stand, as shown and described.

DESCRIPTION

FIG. 1 is a perspective view of a bottle draining stand showing my new design;

FIG. 2 is a top plan view thereof;

FIG. 3 is a side elevational view, the opposite side being identical thereto;

FIG. 4 is a bottom plan view thereof; and

FIG. 5 is an end elevational view, the opposite end being identical thereto.
